UNITED STATES PATENT OFFICE.

ALBERT COHN, OF LONDON, ENGLAND.

DESIGN FOR A COFFEE-PERCOLATOR.

45,585.

Specification for Design.

Patented Apr. 14, 1914.

Application filed January 29, 1914. Serial No. 815,314. Term of patent 7 years.

To all whom it may concern:

Be it known that I, ALBERT COHN, a subject of the King of Great Britain, residing at 114 Queen Victoria street, in the city of London, England, have invented a new, original, and ornamental Design for a Coffee-Percolator, of which the following is a specification, reference being had to the accompanying drawing, forming part thereof.

Figure 1 is a perspective view of the improved coffee percolator, and Fig. 2 is a similar view of part of a machine detached.

a is a bifurcated base having mounted upon it a standard to which is applied a handle *b* of insulating material and the upper part of which terminates in a swan neck

c, at the extremity of which is a clip *d* one part of which is hinged and secured by a screw *e*. This clip *d* receives the neck *f* of a glass vessel *g* into which neck is fitted the lower taper end *h* of a container *i* having formed integral with it a pipe *j* which depends into the vessel *g* to near the bottom of the latter.

I claim:

The ornamental design for a coffee percolator as shown and described.

ALBERT COHN.
